UNITED STATES PATENT OFFICE

NARA D. GOFF, OF CLINTON, IOWA

WASHBOILER

Application filed December 8, 1927. Serial No. 238,564.

The purpose of the present invention is to produce a washboiler primarily intended for domestic use, of increased utility, efficiency and economy. I have found that if the surface exposed to the heat be increased the contents of the boiler will be brought more quickly to the boiling point and the fuel be more efficiently made use of.

Forms my invention take are illustrated in the accompanying drawings in which Figure 1 is a transverse vertical section through a washboiler embodying my invention; Fig. 2 is a transverse horizontal section through a washboiler; Fig. 3 is a top plan view of the cover; and Fig. 4 is a transverse vertical section of a washboiler embodying my invention in another form.

The washboiler comprises the usual bottom piece 1 which is joined in a suitable manner to the wall member 2. While the form or shape of the washboiler is not material to my invention I have shown the usual or typical form which is somewhat oval in plan having straight sides and more or less circular ends. In this construction there is a single side wall member which runs around the entire washboiler. It is this side member which is marked 2 in the drawings and it cooperates with the bottom member to form the receptacle into which water or other material to be heated is placed and into which the clothing to be boiled may be placed.

The structure so far described is of the usual well known ordinary type. In order to incorporate my invention in full I make certain changes therein or additions thereto.

The bottom 1 of the boiler is perforated and in the perforations are inserted and fastened upwardly extending tubes 3. These tubes 3 may be separated somewhat from the sides 2 of the boiler but I prefer for practical reasons to have the tubes 3 run upwardly in contact with the side wall 2. The tubes and the side wall may thus be fastened together and so lend greater rigidity to the structure as a whole. In the usual washboiler prior to my invention the heat struck only upon the bottom of the boiler and was conducted throughout the contents of the boiler by internal circulation of the fluid only.

By my arrangement however it will be seen the heat reaches not only the bottom of the boiler but rises through the tubes 3 and is thus imparted to the contents of the boiler at all levels.

In order to facilitate or augment the passage of heat through the tubes 3 the side wall 2 may be extended below the boiler so as to form a flange or baffle 4 preferably entirely surrounding the bottom 2 of the boiler and the gas burner or burners or other source of heat.

It will be readily seen that if the bottom of the boiler is smooth and not provided with the flange 4 the heat on striking the bottom will deflect and dissipate. By my arrangement however the heat is restrained by the depending flange 4 which acts as a baffle wall and deflects the heat upwardly through the tubes 3 thus affording increased application of the heat and more efficient use thereof. It will be understood, of course, that the connection between the bottom 1 and the side wall 2 will be made water tight in any usual or suitable manner and likewise the joints between the tubes 3 and the bottom 1 will be made water tight in any usual and suitable manner.

The whole structure may be made of metal and for greater efficiency, metals of the highest heat conductivity may be employed. The tubes 3 may extend to the top of the side wall 2 but when the cover is to be used with the boiler I prefer to extend the tubes 3 higher than or above the side wall 2 and to provide the cover 5 with perforations 6 to receive and pass over the upward extensions of tubes 3. It will be observed that in order to allow free passage of the heat the tubes are open and unobstructed at both ends.

While the tubes 3 may be fastened to the side wall 2 by welding or in any other suitable manner I have shown them as soldered to the side wall 2 in Fig. 2. In Fig. 4 I have shown an optional form in which the cover 5 need not be perforated. In this arrangement I have shown the tubes 3 rising from the bottom 1 and toward their upper ends curved outwardly and passing through perforations in the side wall 2. This arrangement allows

a free passage of the heat which by the baffle or flange 4 is deflected upward through the tubes 3^a which extend through the contents of the boiler and then laterally through the open ends of the tubes in the perforations in the side wall 2.

When the boiler is placed on the ordinary heating stove with a flat surface on which the boiler rests, a series of round holes or perforations can be placed in the flange or baffle, the purpose of the openings being to insure a free passage of hot air currents from both underneath the boiler and outside thereof. This construction will insure a free passage of hot air currents that are radiated from the heating surface directly under the boiler upwardly through and out of the tubes. And the hot air currents arising from the heating surface on the outside or away from the boiler will be drawn or have a tendency to pass into the holes coming into contact with the air currents forming under the boiler the hot air thus combined passing upwardly through and out of the tubes, thereby eliminating the possibility of any vacuum forming underneath the boiler.

Changes may be made from the details here shown embodying my invention.

I claim as my invention:

30 1. In a washboiler, a bottom, a side band, open ended tubes vertically disposed and extending from the bottom upward adjacent to the side band and above the top of the side band, and a removable cover perforated to fit over the upper ends of the tubes and close the washboiler.

40 2. A washboiler comprising a perforated bottom, a side wall extending upward from the bottom, open ended tubes in the perforations extending upward from the bottom within the boiler and adjacent to the side wall and connected thereto, an extension of the side wall below the bottom and adjacent the lower open ends of the tubes and acting as a baffle to deflect heat upward through the tubes, a perforated cover for closing the boiler and extensions on the upper ends of the tubes passing through the cover.

50 3. A washboiler comprising a perforated bottom, a side wall extending upward from the bottom, open ended tubes in the perforations extending upward from the bottom within the boiler and adjacent to the side wall and connected thereto, and an extension of the side wall below the bottom and adjacent the lower open ends of the tubes and acting as a baffle to deflect heat upward through the tubes.

60 4. A washboiler comprising a perforated bottom, a side wall extending upward from the bottom, open ended tubes in the perforations extending upward from the bottom within the boiler and adjacent to the side wall and connected thereto, and a perforated cover for closing the boiler the upper ends

of the tubes passing through the perforations in the cover.

5. In a washboiler, a bottom, a side band extending below the bottom and forming a flange and open ended tubes vertically disposed and extending from the bottom upward in contact with the side band.
